UNITED STATES PATENT OFFICE

2,366,009

VANITY CASE OR COMPACT

John De Pasquale and Alexander Westerman,
Brooklyn, N. Y., assignors to Hardy Metal
Specialties Inc., Brooklyn, N. Y., a corporation
of New York

Application June 6, 1944, Serial No. 538,978

2 Claims. (Cl. 206—37)

This invention relates to a new and improved vanity case or compact.

One of the objects of the invention is to provide a vanity case or the like having novel and improved constructional features, whereby the case is rendered substantially leak-proof and the powder contents thereof adequately airtight sealed when the case is closed.

Another object of the invention is to provide a vanity case or compact having an enlarged powder holding compartment.

Another object of the invention is to provide a vanity case or the like having frame members which can be molded from any suitable plastic or resin, such as cellulose acetate and the like.

Still another object of the invention is to provide a vanity case or the like having a bottom or base section and a cover hingedly connected thereto, said base section and cover having certain novel constructional elements which interlock and nest when the case is closed.

Still another object of the invention is to provide a vanity case or compact which is graceful, attractive and of extremely pleasant and ornamental appearance.

Fig. 1 is a sectional view on the line 1—1 of Fig. 2.

Fig. 2 is a top plan view of the improved vanity case or compact, showing the same in open position.

Fig. 3 is a horizontal sectional view, showing the vanity case in closed position.

Fig. 4 is a fragmental top plan view of the case in closed position.

Fig. 5 is a vertical side elevation of the same.

Referring to the drawing, the improved case comprises the bottom or base section B and the cover or upper section C, both of which are substantially circular and are of complementary shape and size. Base B comprises the open frame member 10 and the disc member 11. Cover C comprises open frame member 12 and disc member 13. Frame member 10 will hereinafter be referred to as the bottom or base frame and frame member 12 as the upper or cover frame.

Frame members 10 and 12 are each molded as a unit from a suitable resin or a suitable thermal setting plastic molding material or the like. The same material is used for making both frame members. Each of said frame members 10 and 12 are formed with the respective inwardly annular offset walls 14 and 15, which serve as shoulders or seats upon which disc members 11 and 13 rest. Disc member 11 is seated upon offset wall 14 and is secured thereto by any suitable adhesive or the like. Disc member 13 is seated

upon offset wall 15 of the cover frame 12 and is secured to said wall by any suitable adhesive or the like. Disc members 11 and 13 consequently close the open portions of frame members 10 and 12 to respectively form a cover mirror compartment and a bottom powder compartment P.

Each of disc members 11 and 13 are identical in all respects and the outer or exposed faces 10 thereof may be covered with leather L, or any other desired ornamental material so as to present an attractive vanity case. Said disc members may be of the same or contrasting color as the frames 10 and 12. The exposed faces of disc members 11 and 13 extend slightly above the outer top faces of frames 10 and 12. As shown in Fig. 5, the top faces of said frames are beveled. Bottom frame 10 also has the integral side wall S.

A circular mirror M is secured to the inner face of upper disc member 13 by means of any suitable adhesive or the like, the diameter of said mirror being smaller than the diameter of said disc member.

As shown in Figs. 1 to 3, the inner or bottom face of upper frame 12 is formed with the integral depending annular rib or boss 16, said rib being spaced from the peripheral edge of mirror M, thus forming the annular space 17 therebetween. It will be noted that said rib 16 is spaced from and does not extend to the outer peripheral edge of upper frame 12. The reference numeral 18 designates that portion of the inner face of frame 12 defined by the outer peripheral edge of said frame and the outer peripheral lateral wall of rib 16.

Upper frame 12 is formed with the integral bearing portion 19 which is disposed between the bearing portions 20—20 of bottom frame 10. Upper frame 12 is hingedly mounted upon lower frame 10 by means of a pin 21 extending through and carried by bearing portions 19 and 20—20.

Diametrically opposite bearing portion 19 of upper frame 12 is the integral outwardly extending and depending finger engaging catch 22, said catch depending below portion 18 and rib 16 of said frame 12. The inner lateral wall of catch 22 is longitudinally grooved to assist in the proper locking and closing of the case. This will hereinafter be described.

Referring now to bottom frame 10, the said frame is formed with the integral upstanding annular wall 23, the said wall forming with the inner face of base disc member 11, a circular 53 powder compartment P for holding face powder

and the like. Bottom frame 10 is also formed with the annular groove or channel 24 which is adapted to receive rib 16 of upper frame 12 when the vanity case is closed. Groove 24 is spaced from the outer peripheral edge of bottom frame 10. Said groove 24 is of sufficient width and depth to completely and snugly receive said rib 16.

The outer peripheral edge of bottom frame 10 is provided with the relatively narrow, integral, circular upstanding flange or lip 25. The outer diameter of bottom frame 10 is slightly larger than the outer diameter of upper frame 12. In effect, flange 25 is a vertical extension of side wall S of bottom frame 10. That portion of the top face of frame 10 which extends to the base of flange 25 and to the outer peripheral edge of annular groove 24 is designated by the reference numeral 26.

As is clearly illustrated in Figs. 1 and 2, bottom frame 10 is formed with the grooved cut-out portion or indentation 27 at a point diametrically opposite the hinge construction of the case. The said cut-out portion 27 is of a sufficient size to receive and resiliently and frictionally engage the catch 22 of upper frame 12. Located adjacent said cut-out portion 27 is the finger engaging lug 28.

The fastening means of the case comprises the finger engaging catch 22 and the finger engaging lug 28. The fastening means operates somewhat in the manner of a pocket book or handbag clasp. Catch 22 is forced in one direction and lug 28 in the opposite direction by respective engagement of the thumb and index finger therewith. The inherent resiliency of frame members 10 and 12 is sufficient to permit catch 22 to be forced out of cut-out portion 27 when the case is opened.

Fig. 3 shows the case in the closed position. In this position, the base B and cover C portions meet in the central longitudinal plane of the case. Rib 16 is received by annular groove 24, the bottom face of said rib abutting the base of said groove. Portion 18 of upper frame 12 abuts portion 26 of bottom frame 10, in face to face relationship. The upstanding annular wall 23 extends into opening 17 formed between the peripheral edge of mirror M and the inner peripheral edge of rib 16, thus securely closing the powder compartment P. The outer lateral face of

wall 23 abuts the inner lateral face of rib 16. The outer peripheral edge of upper frame 12 abuts flange 25.

When cover C is in the closed position which is shown in Fig. 3, the depending portion of catch 22 resiliently and frictionally engages cut-out portion 27 of side wall S of bottom frame 10.

There has been shown a preferred embodiment of the invention but it is clear that numerous changes and omissions can be made without departing from its spirit. We do not wish to be limited to any specific size of vanity case or any specific proportions.

What is claimed is:

1. A container of the character described comprising a base section and a cover section hingedly connected thereto, each of said sections having a frame member formed with an inwardly offset wall, a disc member seated on and secured to each of said offset walls, the frame member of the cover section having an integral annular rib depending therefrom, the frame member of the base section having an annular groove formed therein adapted to receive said rib when the container is closed, said base frame member also having an integral upstanding annular wall, said wall adapted with the inner face of the base disc member to form a circular base compartment.

2. A container of the character described comprising a base section and a cover section hingedly connected thereto, each of said sections having a non-metallic molded substantially circular open frame member formed with an inwardly offset wall, a disc member seated on and secured to each of said offset walls, the exposed faces of said disc members being covered with leather, the frame member of the cover section having an integral annular rib depending therefrom, said rib being spaced from the outer peripheral edge of said cover frame member, the frame member of the base section having an annular groove formed therein adapted to receive said depending rib when the container is closed, said groove being spaced from the outer peripheral edge of said base frame member, said base frame member also having an integral upstanding annular wall, said wall adapted with the inner face of the base disc member to form a circular base compartment.

JOHN DE PASQUALE.
